US00D872573S

(12) **United States Design Patent** (10) Patent No.: **US D872,573 S**
 Kestner et al. (45) Date of Patent: ** Jan. 14, 2020

(54) **FOOD HOLDING BIN**

(71) Applicant: **PRINCE CASTLE LLC**, Carol Stream, IL (US)
 (72) Inventors: **Kyle Thomas Kestner**, Schaumburg, IL (US); **Christopher B. Lyons, Jr.**, Lagrange, IL (US); **Charles B. Hartfelder**, Hanover Park, IL (US); **Zachary N. McCoy**, South Elgin, IL (US)

(73) Assignee: **PRINCE CASTLE LLC**, Carol Stream, IL (US)

(**) Term: **15 Years**

(21) Appl. No.: **29/614,817**

(22) Filed: **Aug. 28, 2017**

Related U.S. Application Data

(63) Continuation of application No. 29/561,751, filed on Apr. 19, 2016, now Pat. No. Des. 809,326.

(57) **CLAIM**

The ornamental design for a food holding bin, as shown and described.

DESCRIPTION

FIG. 1 is an isometric view of a first embodiment of a food holding bin showing the new design.

FIG. 2 is a front elevation of the food holding bin.

FIG. 3 is a rear elevation of the food holding bin.

FIG. 4 is a top plan view.

FIG. 5 is a bottom plan view.

FIG. 6 is a right-side elevation.

FIG. 7 is a left-side elevation.

FIG. 8 is an isometric view of a second embodiment of a food holding bin showing the new design.

FIG. 9 is a front elevation of the food holding bin.

FIG. 10 is a rear elevation of the food holding bin.

FIG. 11 is a top plan view.

FIG. 12 is a bottom plan view.

FIG. 13 is a right-side elevation.

FIG. 14 is a left-side elevation.

FIG. 15 is an isometric view of a third embodiment of a food holding bin showing the new design.

FIG. 16 is a front elevation of the food holding bin.

FIG. 17 is a rear elevation of the food holding bin.

FIG. 18 is a top plan view.

FIG. 19 is a bottom plan view.

FIG. 20 is a right-side elevation.

FIG. 21 is a left-side elevation.

FIG. 22 is an isometric view of a fourth embodiment of a food holding bin showing the new design.

FIG. 23 is a front elevation of the food holding bin.

FIG. 24 is a rear elevation of the food holding bin.

FIG. 25 is a top plan view.

FIG. 26 is a bottom plan view.

FIG. 27 is a right-side elevation; and,

FIG. 28 is a left-side elevation.
